EASEL OR THE LIKE

Louis L. Deal, Rye, N. Y., assignor to Deal Slide-Lock Devices, Inc., New Canaan, Conn., a corporation of New York

Application December 6, 1956, Serial No. 44,098

Term of patent 14 years

(Cl. D29—20)

Fig. 1 is a rear perspective view of an easel or the like, showing my new design;

Fig. 2 is a rear elevational view thereof;

Fig. 3 is a side elevational view thereof; and

Fig. 4 is a rear perspective view similar to that shown in Fig. 1 showing the panel in its retracted position.

The broken line showing of a panel is for illustrative purposes only.

I claim:

The ornamental design for an easel or the like, substantially as shown and described.
